UNITED STATES PATENT OFFICE.

OWEN E. McMAHON, OF ELGIN, ILLINOIS.

GRIPPING DEVICE.

No. 880,090.

Specification of Letters Patent.

Patented Feb. 25, 1908.

Application filed April 23, 1907. Serial No. 369,858.

To all whom it may concern:

Be it known that I, OWEN E. McMAHON, a citizen of the United States, and a resident of Elgin, in the county of Kane and State of Illinois, have invented certain new and useful Improvements in Gripping Devices; and I do hereby declare that the following is a full, clear, and exact description thereof, reference being had to the accompanying drawings, and to the letters of reference marked thereon, which form a part of this specification.

This invention relates to improvements in gripping devices designed to engage an electric wire cable or the like with a gripping force to draw the same forwardly as, for instance, through an under-ground conduit, and the invention consists in the matters hereinafter set forth and more particularly 20 pointed out in the appended claims.

Among the objects of my invention is to produce an improved gripping device for this purpose of extremely simple and efficient construction, and one wherein the tractive 25 or pulling force is exerted on the device in a manner to increase the gripping action on the cable.

In the drawings:—Figure 1 is a side elevation of a gripping device made in accordance 30 with my invention. Fig. 2 is a central longitudinal section thereof. Fig. 3 is a plan view. Fig. 4 is an end view. Fig. 5 is a section taken on line 5—5 of Fig. 2.

As shown in the drawings, A A¹ designate 35 two elongated gripping jaws. Said jaws are hinged one to the other at the rear end of the device. The hinge, in the present instance, consists of two laterally separated, rearwardly directed, oblique arms a a on the 40 lower jaw provided with inwardly extending hinge lugs a¹ and two rearwardly directed, oblique arms a² a² on the upper member provided with rearwardly opening notches or sockets adapted to receive said lugs. The 45 said gripping jaws are provided with elongated gripping faces a³ a³ which extend to the rear end of the device. The said gripping faces are shown as made transversely concave to receive the round or cylindric 50 cable. The space between the jaws opens rearwardly through the rear end of the device so as to permit a cable to be inserted into said space through said rear opening. The laterally separated hinges are spaced a 55 distance apart to freely receive therebe-

tween a cable and said hinges are located one at each side of said rear opening.

B designates a tractive or pulling link that is connected with the forward end of the device and is adapted for attachment thereto of a pulling chain or cable. The said link embodies or is combined with features of construction which coöperate with the link to serve as a means for locking the jaws pressed upon an interposed cable, and said locking means are so arranged that the grip impressed on the cable by the jaws is proportional to the tractive force or pull tending to pull the cable forwardly. For this purpose the said link B comprises a forwardly extending loop b to which a drawing or pulling chain or cable is adapted to be attached, one end member b¹ of which extends through a slot c of a hook extension C made integral with a neck a⁴ which extends forwardly from the lower jaw A¹. Extending rearwardly from said link B is a closed locking loop B¹, made somewhat larger than the loop b, and the rear end member b¹ of said locking loop is adapted, when the link is in its normal or 75 pulling position, to occupy a rearwardly and upwardly inclined notch c¹ in said hook extension; said notch giving to this part of the device the general form of a hook as shown in Figs. 1 and 2. The upper jaw A is provided with two forwardly extending arms D D, one on each side of the shank a⁴. The forward ends d of said arms D are inclined forwardly and upwardly and lie with their inclined upper margins closely adjacent to 80 the rearwardly and upwardly oblique notch c¹ of the hook extension C. The upper margins of said inclined portions of said arms intersect or extend across the lower margin of said notch c¹, as shown in Fig. 1 and are, 85 therefore, in position for engagement by the rear end member b² of the locking loop. 90

In the use of the device, the pulling link is shifted rearwardly until the rear end member b² of the locking loop extension is out of 100 the notch c¹, whereupon said link may be swung about the part b¹ to the position indicated in dotted lines in Fig. 1, in which position the said locking loop is free from the forwardly extending arms of the upper jaw. 105 The said upper jaw may now be swung away from its companion jaw sufficiently to permit a cable to be inserted through the rear open end of the device between the gripping faces of said jaws. Thereafter the jaws are closed upon 110

the cable and said link is rearranged to bring the closed end b^2 of the locking loop extension into the notch and into engagement with the upper inclined margins of the locking 5 arms D, as shown in dotted lines in Fig. 1. If now a draft or forward pull be exerted upon said link it will be obvious that the effect of the co-action of said closed end b^2 of the locking link with the inclined margins of said locking arms D has the effect, not only to draw the device and the gripped cable forwardly, but also to clamp or grip the jaws tightly against the cable, and it is further evident that this gripping action is 10 proportional to the pulling force exerted to draw the device and the cable forwardly.

In order to effect an efficient bite of the jaws against an interposed cable, the inner faces of the jaws are provided with opposing 15 gripping lugs a^5 a^5 located out of line with each other. Said gripping lugs are shown as being transversely concave to correspond generally to the contour of the cable gripped thereby. The said lugs, which may be supplemented by others, constitute a roughened 20 surface which engage the interposed cable in a manner to somewhat bend or distort the same out of a straight line and therefore produce a more efficient gripping action of the 25 jaws upon the cable.

I claim as my invention:—

1. A gripping device comprising two jaws hinged together at their rear ends, a pulling link having slotted connection with the forward end of one of the jaws, said latter jaw being provided with an inclined notch and an inclined surface on the forward end of the other jaw, and a part on said link engaging said notch and inclined surface and operated 30 by the pulling force on the link to force said jaws together.

2. A gripping device comprising two jaws hinged together at their rear ends, a pulling link provided with a transverse member 35 having slotted connection with the forward end of one of the jaws and provided with a rearwardly extending locking loop, said other jaw being provided with an inclined surface adapted for engagement by said locking loop, as and for the purpose set forth.

3. A gripping device comprising two jaws hinged together at their rear ends, one of 40 said jaws being provided at its forward end

with an inclined notch and the other jaw with an inclined surface adjacent to said notch, and a pulling link connected with said first jaw and provided with a locking member occupying said notch and adapted to engage said inclined surface, as and for the purpose set forth.

4. A gripping device comprising two jaws hinged together at their rear ends, one of said jaws being provided at its forward end with an inclined notch and the other jaw with an inclined surface adjacent to said notch, and a pulling link connected with said first jaw and provided with a locking member occupying said notch and adapted to engage said inclined surface, said link having slotted connection with its associated jaw, 65 permitting the locking member to be disengaged from said notch.

5. A gripping device comprising two jaws hinged together at their rear ends, one of said jaws being provided with a slotted extension and with a rearwardly opening inclined notch and the other jaw being provided with a forwardly inclined arm adjacent to said notch, and a drawing or pulling link having sliding connection with said slotted extension and provided with a rearwardly directed locking loop, a part of which occupies said inclined notch and is adapted 70 to engage said inclined arm, as and for the purpose set forth.

6. A gripping device comprising two jaws hinged together at their rear ends by laterally separated hinges and constructed to provide between the hinges a rearwardly directed opening to receive a cable to be gripped, a pulling link having slotted connection with the forward end of one of the jaws, said latter jaw having an inclined notch, an inclined surface on the forward end of the other jaw, and a part on said link and engaging said notch and inclined surface, for the purpose 75 set forth.

In testimony, that I claim the foregoing as my invention I affix my signature in the presence of two witnesses, this 23rd day of 80 March A. D. 1907.

OWEN E. McMAHON.
